SEWING MACHINE FOR THE MANUFACTURE OF GLOVES

Walter Lindner, Pleissa, near Limbach, Germany,
assignor to Firma Johannes Richter A.-G.,
Limbach, near Chemnitz, Germany

Application March 4, 1932, Serial No. 596,819
In Germany March 11, 1931

5 Claims. (Cl. 112—162)

My invention relates to machines for making gloves and more especially to an improved sewing machine for the production of such gloves, which may be made of any suitable material, preferably 5 knitted textile fabrics, such as imitation "Swede" and kindred specially made "glove" fabrics. They may also be made of other kinds of fabrics, such as cotton, wool, silk, artificial silk, linen etc., and including double cloth, sateens, polished, 10 fleeced and chemically treated fabrics, and leather.

The objects of the invention and the advantages obtained thereby will be better understood by first briefly reviewing the state of the art in 15 this field of manufacture:

Various manufacturing methods referred to in detail hereinafter are known in the manufacture of gloves. The principal features common to all those methods are that the different cuttings of 20 which the gloves consist—trunk, fourchettes, thumb, and gussets—are sewn together along their circumferential edges, and that for the production of gloves of widely different trade sizes including the smaller, the medium and the largest 25 sizes, of some cuttings—including fourchettes and thumbs—only a few standard sizes are available from which also the gloves of the intermediate viz. next smaller sizes are to be made. Said methods however widely differ from each other 30 as to the position in which the cuttings are assembled upon or along each other while being sewn together, and as to the type of seamings applied in each case, depending on the type and construction of the respective sewing machines used.

Gloves manufactured with the aid of sewing machines of types and design known heretofore are not giving complete satisfaction for various reasons referred to in detail hereinafter, although much care is generally devoted to overcome the many difficulties arising in the production of gloves, and although a relatively large percentage of gloves is discarded in the course of their manufacture as being defective.

Referring first to gloves made from rather stout leather, these are made in many cases by sewing together the cuttings with their edges partly overlapping each other. Thereafter the edges or strips of material projecting over the seams on the inside and the outside of the glove are cut off by hand, and the seamings are carefully trimmed.

In the manufacture of gloves of thinner and softer leather, such as kid, chamois leather and the like, the pieces of material are sewn together 50 at their edges with closed seams on lock stitch

machines or with overseams, so-called "glovers" seams, on double thread overseaming machines of special design, and cutting devices of special design cooperatively associated with the sewing members are used for cutting off the protruding 5 edge portions during the sewing operation proper.

However, as these cutting devices had to be arranged in close proximity to the sewing members of the machine, the space available for the cooperation of the thread guiding, loop forming, material supporting, feeding and other vital members of the sewing machine, and for freely manipulating the glove especially in sewing sharply bent sections such as the finger tips is seriously obstructed by the knives with the result that the 10 latter will often cut radially into the said sharply bent sections of the glove, that the whole structural design of those sewing machines will become extremely complicated, and that it will be 15 a difficult task even for the most skilled seamstresses to keep the machines in good working order.

Moreover in using double thread overseaming machines for joining the edges of the cuttings concerned, the needle often takes too little of the material under treatment, viz. leaving a too narrow margin, so that even double thread stitches proved not to be sufficiently resistive against becoming undone; or else the needle will accidentally take no material at all at some places so that 20 a number of stitches are missed entirely, and a toppling overseam is obtained.

By reason of occurrences of this kind a great percentage of defective gloves are produced which are unsightly in their appearance and little resistive against wear and tear, viz. liable to break 25 at the defective seamings.

Defects and difficulties similar to those referred to hereinbefore with reference to leather gloves also occur in the manufacture of gloves made of 30 cuttings from textile fabrics briefly called hereinafter fabric gloves.

A method much in use of producing fabric gloves consists in placing the cuttings in reversed position upon each other, viz. with their wrong 35 sides out, sewing together their circumferential edges on lockstitch or chainstitch machines, and eventually reversing the gloves.

As a matter of fact it is impossible to avoid, in sewing, the formation of those well known bulging seamings, which although being inside the gloves are particularly objectionable at the finger tips, causing real discomfort to the wearer in the case of tightly fitting gloves, while loosely fitting 40 gloves at least have an unsightly appearance.

Also in cases where it is preferred to sew the textile fabric cuttings together with their right sides without and with lap seams so as to avoid the reversing of the gloves, bulging ridges and projecting warts are produced on the outside of the gloves along the fingers which discredit the gloves as to their appearance.

The principal object of my invention is to overcome the various drawbacks referred to above by providing an improved overseaming sewing machine of relatively simple design for their manufacture.

In connection therewith the invention aims at thus designing the sewing machine, that three thread overseamings of relatively narrow width, narrower than known before are produced at the edges of the gloves which are uniform and decorative in their appearance and have great strain resisting properties.

Other objects of the invention will incidentally become apparent hereinafter to experts in the sewing machine field.

The nature and scope of the invention is briefly outlined in the appended claims and will be more fully understood by the following specification taken together with the accompanying drawings in which

Fig. 1 is a side elevation showing an improved sewing machine designed according to this invention,

Fig. 2 shows the principal members for guiding and looping the threads in their lowest position underneath the throat plate on a larger scale,

Figs. 3, 3a, and 3b show the same members in an intermediate position ready for forming the loops, jointly with the throat plate, the cloth feeding, pressing and guiding members on a larger scale,

Fig. 4 shows the seam forming members in their highest position relatively to the throat plate,

Figs. 5 and 6 show the throat plate and the presser foot respectively from different angles.

My experiments have shown that gloves of superior quality as to their correct fit, durability and resistance against wear and tear, neatness in appearance and absence of objectionable warts and bulging ridges referred to above, are obtained by providing sets of cuttings including trunk, fourchettes, thumb, gussets—of individual size and shape for each trade size of gloves, viz. by so designing said cuttings that they match each other at their circumferential edges with so high a grade of accuracy,—higher than known heretofore—that no protruding edge portions need to be cut off during the following manufacturing steps,—superposing the respective complementary cuttings with their edges flush to each other and sewing them together with triple thread made overseamings of relatively narrow width—narrower than known heretofore—on a triple thread overseam sewing machine presenting the specific structural features described hereinafter.

As seen in Fig. 1 the principal members of the sewing machine are a frame on which a reciprocating rod 10 carrying the needle 9 is mounted, the machine being actuated by hand or mechanical power through a driving mechanism of known design. Said driving mechanism and some other accessory members such as thread tensioning and pulling devices are also diagrammatically indicated in Fig. 1 of the drawings but will not require any description in detail. Since Fig. 1 is a diagrammatical representation of a sewing machine the member 15 as shown in Fig. 3 has been omitted therefrom.

The work plate has been omitted in the drawings in order to more clearly show the thread carrying and seam forming members and their actuating mechanism, which are or at least can be of known design.

The members cooperating with the reciprocating rod 10 and needle 9 comprise an oscillating hook 11, carrying and looping one of threads, and another oscillating hook 12, which is arranged beneath the cloth feeder 13 and throat plate 14 and is adapted to carry and loop another thread. The said hooks 11 and 12 are shown in Fig. 1 in their uppermost position and of the presser foot only the foot plate 15 is shown, while other detailed parts known per se and not being essential for elucidating the cooperation of the thread carrying and looping members have been omitted in the drawings.

According to this invention an arm 16 of special shape and having different functions referred to hereinafter is arranged at the front side of the machine frame so that its lower end 16a bears against the throat plate 14 closely to the needle opening, while its upper end bears against a stop adjustably mounted on the machine frame in such manner that the arm 16 can be set into its appropriate position and is held in the latter.

Referring now to Figs. 2-6 in which the principal members of the improved sewing machine are shown in a larger scale: Fig. 2 shows the needle 9 being in its lowermost position; equally the hooks 11 and 12 which carry threads at their perforated ends 11a and 12a respectively are in their lowest positions, hook 11 being formed with a nave 11b and being mounted on a shaft (not shown) so as to be swung up and down as seen in Figs. 2-4.

The cloth feeder 13 is formed at the lower side of its toothed section with bevelled faces 13a, 13b so as to provide ample working space for the hook 11a, enabling the latter to get as closely as possible underneath the upper face of the cloth feeder and the throat plate 14.

In Figs. 3 and 4 the thread carrying and seam forming members 9, 11, 12 are shown in an intermediate and in their uppermost position respectively: While the needle 9 rises upwards from its lowest position a loop is formed which is caught by the hook 11a and is pulled over the latter; thereafter, viz., while the hooks 11 and 12 are approximately in the position shown in Fig. 3 the thread carrying end 12a of hook 12, enters the loop of the thread carried by hook 11a and pulls said loop over itself.

Eventually the needle 9, on being approximately in the position shown in Fig. 4, enters the loop of the thread carried by hook 12a so that the said loop is equally locked.

While the glove under treatment is pushed forward by the cloth feeder 13 the loops are all pulled together through the action of the thread tensioning device, referred to above, and a triple thread overedge stitch is obtained of which all the threads are securely interlocked.

According to this invention the throat plate 14 seen in Figs. 3, 3a, 3b, and 5 is specially designed so that a very narrow seam is obtained; I have found it desirable for this purpose—especially in the case of rather thin fabrics,—to arrange the needle opening, the needle, the cloth carrying and guiding members and the thread carrying hooks as closely as possible to each other, and near that edge of the throat plate which is directed toward the driving mechanism of the machine.

Owing to this arrangement however the cloth feeder and presser must be also in close vicinity to the said edge of the throat plate whereby the available working space is reduced, and it has become necessary for me to thus design the seam forming members that they do not mutually obstruct the space required for their work.

This problem has been solved in the following manner: As seen in Fig. 5, comprising a plan of 10 the throat plate 14 the needle opening has been ostensibly displaced towards the said free edge of the throat plate and has been brought into close quarters with a thorn-like projection 14a; the latter is so designed that the threads are caused 15 to slide off in the desired form.

The said thorn 14a of which Fig. 5 presents also a side elevation has a tapering recess at its lower face so designed that the hook 11a can pass closely underneath said thorn which is a 20 rather delicate yet important member of the sewing mechanism.

In Fig. 3a containing a section taken approximately through the needle opening of throat plate 14 the curved lower face 14d of a member from 25 which said thorn 14a projects can be seen in a larger scale.

Fig. 5 showing the throat plate 14 in plan and in cross section will make clear—jointly with Figs. 3 and 3a the shape of the recesses or slits 30 which are provided in the throat plate, one on each side of the bridge member 14b in which recesses the cloth feeder 13 moves with its toothed portions 13a, and 13b.

In Fig. 3b there is diagrammatically indicated 35 in dotted lines on top of the cloth feeder the specific form of the foot plate of the cloth presser 15, the latter having two sections 15a and 15b.

The said cloth presser 15 is shown from three 40 different angles in Fig. 6. From this figure it appears that the said foot plate 15 is provided with several bevelled edges, viz, one at its front section 15b, another one at its rear section 15a, a third one at the corner 15c and others at the 45 offsetting points of transition between the sections 15a and 15b.

By thus shaping the cloth presser 15 an advantage of great importance is obtained which consists therein that the glove under treatment—although being firmly held in its various positions—can yet be readily turned around even at 50 very sharply curved seams, and in most cases even without lifting the cloth presser; by reason of this feature seamstresses will be able to produce gloves having faultless seamings even around the finger tips.

Figs. 3 and 3a will make it clear how it has been accomplished that all the seam forming members can readily move and cooperate, without interfering with each other, within the limited space 60 underneath the throat plate and in close proximity to the front edge of the latter.

According to this invention the sewing of gloves with this machine is greatly facilitated by the provision of a guide arm 16, referred to above and 65 being shown in Figs. 1, 3, 3a, and 3b. Said arm is pivotally mounted on the machine frame by a screw 16d and bears against stop 11, 11a secured to the machine frame by a screw 17b. Arm 16 is a guide member serving several purposes, viz. 70 guiding the edge of the materials, supporting the throat plate, and finally protecting the fingers of the seamstresses and providing a kind of rest or support for her fingers.

The lower end of said guide arm 16 which bears 75 against and acts as a support to the throat

plate 14 is provided with a sloping face 16a which is arranged closely to the needle opening, said configuration facilitating the turning of the gloves in curved sections of their seamings and providing a maximum of space for the formation 5 of the seam.

By reason of the glove under treatment being guided from above by arm 16 the glove is secured against accidentally slipping off, and in addition 10 the delicate parts of the throat plate are effectively supported by the said arm and in such manner that the work of the thread carrying and loop forming members, more especially of the hooks 11a, 12a, is not interfered with.

From Figs. 3 and 3a it will be seen that the said 15 arm 16 is a good support for and protects especially the right hand of the seamstress, which is an equally important feature, if one realizes that the upper face of the work plate of the machine 20 is generally formed with a vaulted section which covers up especially the hook 11a and also partly the movement of the hook 12a.

It will be obvious to experts in this field that 25 various changes and modifications may be made in the structural design of overedge sewing machines having the features described and shown in the drawings and in the manner of manufacturing gloves with those machines set forth above without deviating from the spirit and the salient 30 ideas of my invention.

What I claim is:

1. A triple thread overseaming machine particularly for gloves, comprising a throat plate; an arm in the form of a guide finger for the glove; 35 a presser foot; a cloth feeder, said foot and feeder being arranged in close proximity to the free edge of the throat plate and the throat plate having a thorn member; and a stop member mounted on the machine, said throat plate, cloth feeder, thorn member and presser foot having recesses and bevelled edges to provide a working space for the seam forming members enabling them to interlock the threads closely at the outer edge of the throat plate and in close proximity to the needle opening to produce an overedge seam of 40 relatively narrow width at the same time to provide ample space for the manipulation of the glove.

2. A triple thread overseaming machine according to claim 1, in which the arm at its upper section bears against the stop and the lower section of the arm bears against a bevelled edge of 50 the throat plate adjacent to the needle opening.

3. A triple thread overseaming machine particularly for gloves, comprising a throat plate; an arm in the form of a guide finger for the glove; and a stop member mounted on the machine, said arm at its upper section bearing against the stop and the lower section of the arm bearing against a bevelled edge of the throat plate adjacent to 55 the needle opening in the plate.

4. A triple thread overseaming machine particularly for sewing together the parts of a glove, comprising a throat plate; a thorn member on the throat plate defining therewith a needle opening; a guide finger for the glove to be sewed cooperating with and supporting the throat plate; driving members for the machine; thread guiding and seam forming members; a presser foot; and a cloth feeder arranged in close proximity to the free edge of the throat plate, the throat plate, cloth feeder, and presser foot having recesses and bevelled edges to provide a working space for the seam forming members enabling them to inter- 70

lock the threads closely at the outer edge of the throat plate and in close proximity to the needle opening and to produce an overedge seam of relatively narrow width, at the same time providing ample space for the manipulation of the glove to be sewed even around sharply bent curves.

5. A triple thread overseaming machine particularly for sewing together the parts of a glove, comprising a throat plate; a thorn member on the throat plate defining therewith a needle opening and having a pointed thorn; a guide finger for the glove to be sewed; driving members for the machine; thread guiding and seam forming members; a presser foot; and a cloth feeder arranged in close proximity to the free edge of the throat plate, the throat plate, cloth feeder, and presser foot having recesses and bevelled edges to provide a working space for the seam forming

members enabling them to interlock the threads closely at the outer edge of the throat plate and in close proximity to the needle opening and to produce an overedge seam of relatively narrow width, at the same time providing ample space 5 for the manipulation of the glove to be sewed even around sharply bent curves, and said guide finger bearing at its upper section against a stop, the lower section of said guide finger bearing against a bevelled edge of the throat plate closely 10 to the needle opening, and being so designed as to support and protect the fingers of the operator, and at the same time to support and protect the pointed thorn and to act as a guiding member for the glove both in cases when straight and sharply bent edges, such as the finger tips of the glove, are being sewed together.

15 WALTER LINDNER.
